Richard C. Ewald,
Attorney

UNITED STATES PATENT OFFICE.

THOMAS N. COFFELDER, OF CINCINNATI, OHIO, ASSIGNEE, BY MESNE ASSIGNMENTS,
TO LIBERTY RADIATOR COMPANY, OF PITTSBURGH, PENNSYLVANIA, A CORPORA-
TION OF PENNSYLVANIA.

RADIATOR.

1,836,999.

Specification of Letters Patent. Patented Apr. 13, 1920.

Application filed March 24, 1917. Serial No. 157,092.

To all whom it may concern:

Be it known that I, THOMAS N. COFFELDER, a citizen of the United States, and a resident of Cincinnati, in the county of 5 Hamilton and State of Ohio, have invented certain new and useful Improvements in Radiators, of which the following is a full, clear, and exact description, reference being had to the accompanying drawings, forming 10 a part of this specification.

My invention relates to improvements in radiators and particularly to such radiators as are intended and adapted for use on motor vehicles.

15 One object of my invention is to provide a radiator of the character mentioned of simple and inexpensive construction.

A further object of my invention is to 20 provide a radiator for motor vehicles of great cooling efficiency.

Heretofore it has been the practice in assembling the core of a radiator of the tubular type, to secure the tubes and fins together by means of soldering. It is the object of 25 my invention to provide means whereby the said parts may be assembled without the use of solder to secure the same together, thereby simplifying the construction and rendering the radiator more durable.

30 A further object of my invention is to provide in a radiator of the character mentioned radiating fins so constructed that portions of said fins may alternate between vertically disposed tubes and present vertical front edges similar to the front edges of said tubes, so that increased radiating efficiency may be obtained with a comparatively small number of tubes and still maintain the uniform and neat appearance of 35 the radiator when viewed from the front.

Further objects of my invention will appear from the following description thereof.

In the drawings:

Figure 1 is a front elevation of an automobile radiator constructed in accordance 45 with my invention.

Fig. 2 is a perspective of a portion of the core of said radiator.

Fig. 3 is a perspective of a part of one 50 of the radiating fins.

Fig. 4 is a perspective of a modified form of radiating fin, with a tube to show the manner of assemblage.

The numeral 1 indicates the upper tank 55 and 2 the lower tank of a radiator adapted

for use on motor vehicles. The said tanks are of any desired and suitable construction. Between the said tanks 1 and 2 are vertically disposed tubes 3, the ends of said tubes being secured to said tanks in any 60 suitable manner to prevent leakage. Each of the tubes 3 is made of a strip of sheet metal, the said strip being folded over and the edges soldered or otherwise secured together as shown at 4. The tubes as thus 65 constructed, have but a single seam and the tube thus presents, along the said seam, a knife edge. At regular intervals along the edges of the tube are notches 5 within which the radiating fins are adapted to be mounted 70 in such a manner that the edges of the tubes and said fins will be in the same plane.

The numeral 6 indicates the radiating fins of my radiator. Each of said fins is composed of a strip of sheet metal, as for instance, copper, the same being provided with slots 7 at regular intervals throughout their length. The front ends of said slots are narrowed as shown at 8, and extend to 80 points near the front edge 9 of the fins, the distance between the slots and the edge of the fin being equal to the depth of the notches 5 in the edges 4 of the tubes. At the rear end of each of the slots, the fin is slit 85 so that a portion 10 may be bent back to permit the insertion of the tube. After such insertion, the portion 10 is returned to its original position, thus securing the tube in place with the slot 5 in engagement with the 90 front edge of the fin. Between the slots 7 in the fin are folds forming flanges 11, the width of said flanges being approximately equal to the distance of the flange from the adjacent slots 7. 95

In assembling the core of the radiator, a suitable number of tubes 3 are placed in the slots 7 of the required number of fins 6, the notches 5 of the tubes engaging the metal of the fins in front of the slots, and 100 the said tubes being held in position by means of the portions 10 of the fins. The front edges of the tubes and fins thus lie in the same plane. Between each pair of tubes is an edge corresponding to the front vertical edges of the tubes composed of flanges 11 on the horizontally adjacent fins, all of said flanges registering vertically as shown in Fig. 2 of the drawings. When thus assembled, as will be seen, the core, when 110

viewed from the front, comprises a series of vertical and horizontal edges in the same plane; alternate vertical edges being the edges of tubes, and those between being composed of flanges of the radiating fins, the whole presenting a uniform and neat appearance.

In Fig. 4 I have shown a modified form of radiating fin in which provision is made for double the number of tubes provided in the form of core shown in Fig. 2, the flanges 11 being done away with. As so constructed, the radiating fin is composed of a strip 12 provided with slots 13 of substantially the same construction shown in Fig. 2, the said slots however, being somewhat longer than the tubes to permit the insertion of same. When inserted, and the notches 5 brought into engagement with the front edge of the fin, the rear portion of the fin is doubled over so that the rear edge abuts against the rear of the tubes thus securing the tubes in the slots, the front edges of the tubes being secured by the notches 5.

25 The fins when constructed either as shown in Fig. 3 or Fig. 4 of the drawing may, if desired, be provided with perforations 14 which add greatly to the radiating efficiency of said fins.

30 From the foregoing description, the nature and construction of my new radiator will be apparent to those skilled in the art. When constructed of tubes as above described and of radiating fins either as shown 35 in Fig. 3 or Fig. 4, the parts may be readily assembled without soldering; and the core presents a uniform and neat appearance from the front. In the case of the fin shown in Fig. 3 however, only alternate vertical 40 edges represent tubes, whereas in the construction disclosed in Fig. 4, each of the vertical edges represents a tube. It will be noted that the construction of a radiator comprising the details above set forth is a 45 matter of great simplicity and of comparatively small expense and labor. A radiator constructed furthermore in the manner above set forth is of high radiating efficiency, either when provided with the fins 50 shown in Fig. 4 or in Fig. 3. In the latter construction, the flanges 11 give increased

radiation, and this construction is thus substantially as efficient as when an unbroken series of vertical tubes is provided. The perforations 14 of the fins of course add 55 greatly to the radiating efficiency thereof. A radiator constructed substantially in accordance with the present invention, as will readily be seen by those skilled in the art, may be used also as a condenser for steam 60 cars and for similar purposes.

Having thus described my invention, what I claim as new and desire to secure by Letters Patent is:

1. A radiator core comprising a series of 65 flat tubes having plain unbroken inner and outer surfaces and of a width to extend substantially from the front to the rear of the core and provided in one of their edges with spaced notches, in combination with a series 70 of fins provided with slots to receive said tubes and having one edge unbroken and engaged in the notches in the tubes and the other edge being provided with means for holding the unbroken edge in said notches. 75

2. In a radiator, a core comprising a series of vertical tubes, each of said tubes being provided with a front knife edge, a series of radiating fins, each of said fins being provided with a series of vertical flanges, and 80 means whereby said tubes and fins may be assembled in such a manner that the tubes and the vertical flanges alternate, and that said flanges on adjacent fins may register to present continuous edges corresponding 85 in appearance to the knife edges of the tubes.

3. In a radiator, a core comprising a series of vertical tubes each of said tubes being provided with a front knife edge and a series of notches at regular intervals in said edge, 90 a series of radiating fins, each of said fins comprising a strip provided with slots and having a series of vertical flanges alternating with said slots, said slots being arranged to receive said tubes and to engage in the 95 notches therein so that the front edges of said tubes and fins will be disposed in the same vertical plane and the flanges on adjacent fins will register to present continuous edges corresponding in appearance to 100 the front edges of the tubes.

THOMAS N. COFFELDER.
